UNITED STATES PATENT OFFICE.

STANLEY M. RAMSEY, OF CINCINNATI, OHIO.

WRAPPING-PAPER FOR LOAVES OF BREAD AND THE LIKE.

1,171,461.

Specification of Letters Patent. Patented Feb. 15, 1916.

Application filed March 15, 1915. Serial No. 14,563.

To all whom it may concern:

Be it known that I, STANLEY M. RAMSEY, a citizen of the United States, and a resident of the city of Cincinnati, in the county of 5 Hamilton and State of Ohio, have invented certain new and useful Improvements in Wrapping-Paper for Loaves of Bread and the like, of which the following is a full, clear, and exact description, reference being 10 had to the accompanying drawings, forming part of this specification.

In recent years, for the purpose of preventing bread and the like from drying out and becoming unfit for use, it has been customary to wrap such material whether by hand or automatic machinery, in waxed or paraffined paper, supplied from the roll or in sheets, to be folded and tied with string, secured by gummed stickers, or when desired, 20 in order to cause the folded ends of the wrapper to adhere for properly sealing the package, by the application of heat and pressure to the overlapping parts. To accomplish this last result satisfactorily, the 25 percentage of wax for the paper must be much higher than would be ordinarily required merely to prevent the passage of air and moisture. It has been found, however, that the wrapping of bread in waxed paper 30 is not entirely satisfactory in that the holding of moisture in the crumb and crust and the lack of ventilation injuriously affect the bread resulting in the formation of mold and the development of a musty taste in the loaf.

35 The bread is frequently wrapped containing residual heat when fresh from the oven, and the paraffin wax being a poor conductor of heat retains this heat which, with the retention of the moisture, largely enhances the 40 conditions favorable for mold development.

To overcome this difficulty, attempts have been made to secure ventilation by perforating the sheet but, of course, at the expense of the sanitary requirements incident to a 45 completely wrapped package. The problem presented, therefore, is to provide a wrapping paper which shall furnish the proper degree of ventilation, obviating the retention of heat and moisture conducive to mold development, at the same time that the sanitary 50 conditions of the exclusion of dust and dirt are maintained.

To accomplish this result is the object of my invention and it consists in the production of a wrapper to be hereinafter described 55 and claimed in which provision is made for

a sufficiently heavy waxed coating in connection with unwaxed strips or sections for ventilation and release of moisture.

In the drawings, Figure 1 is a plan view, 60 and Fig. 2 is a transverse section of my wrapper.

The wrapper consists of a sheet of suitable thin paper 1, to which for sealing by heat a thick coating of paraffin has been applied 65 for the outer ends 2, 2, which ends in wrapping are folded over and sealed by heat and pressure in the usual way. For the intermediate portions of the wrapper I leave a strip or strips 3, 3, to which no wax or 70 paraffin has been applied. The width of these unparaffined portions may vary as may be desired, but I prefer to provide alternate strips of waxed and unwaxed material as shown. 75

In the manufacture of my paper, the material is treated with the waterproofing material in the web as it comes from the roll, and at the conclusion of the treatment the paper is cut to the proper size for the wrappers. In applying the waterproof material, 80 a sufficiently wide strip is coated so that when cut each sheet shall be provided with both waxed and unwaxed portions.

In order to permit the web to be properly 85 and tightly rolled after the same is coated with the waterproofing material at the ends, it is preferable to leave alternate strips of coated portions with the uncoated portions. Otherwise in mounting in rolls the difference 90 in thickness of the ends and middle portion would lead to difficulties in thickness. The width of the alternate strips is a matter of selection to suit the requirements of the particular grade of paper under treatment and 95 may be varied as desired.

When the wrapper has been manufactured as described, I have all the advantages of a wrapper furnishing the proper amount of ventilation at the same time that the dust and dirt are fully excluded. The bread can be wrapped in the bread wrapping machines in which the sealing by heat is employed without any alteration or modification of such machines, and also in machines, where 100 gummed stickers or string are employed for securing the package, the paper being supplied directly from the roll or in sheets. 105

Having thus described my invention, what I claim as new and desire to secure by Letters Patent, is:

1. A wrapping paper for bread and the

like, comprising portions of waxed and unwaxed areas in such relative proportions as to secure the desired ventilation.

2. A wrapping paper for bread and the like, comprising alternate strips of waxed and unwaxed areas in such relative proportions as to secure the desired ventilation.

3. A wrapping paper for bread and the like, having its side edges coated with waterproof material sufficiently heavy to adhere to each other when subjected to heat and pressure, and with intermediate portions of the sheet free from waterproof coating.

4. A wrapping paper for bread and the

like comprising alternate strips of waxed and unwaxed material, with waxed edges for sealing under heat and pressure.

5. A wrapping paper for bread and the like comprising alternate strips of waxed and unwaxed material, with waxed edges for sealing under heat and pressure, the waxed strips being sufficiently close to maintain a substantially uniform thickness for the sheet when winding into a roll.

STANLEY M. RAMSEY.
